Spars Mathew
ATTORNEY

UNITED STATES PATENT OFFICE.

ANDREW J. STEWART, OF LEBANON, INDIANA.

LATCH.

Application filed April 17, 1926. Serial No. 102,791.

The present invention relates to an improved automatic latch and handle, and has for an object to provide a latch of this character of simple, strong, and inexpensive construction, and which will be efficient and reliable in operation. A particular object of the invention is to provide a latch connected to an operating handle, constituting the knob or handle of the door, and which handle upon being pulled in the direction to open the door will automatically release the latch; and as one feature of the invention, it is proposed to provide a connection between the handle and latch by means of which the door may be closed by pressing inwardly upon the handle, and at the same time permitting the latch to have free retracting and keeper engaging movement as the door is pressed to its fully closed position. To this end, the invention, according to one embodiment, consists in providing a spring actuated latch adapted to have retractive movement independently of the handle through pressure applied at the nose, and a spring actuated handle connected to the latch, having a normal position independent of the latch, and adapted upon being pulled outwardly in opening the door to automatically release the latch.

Heretofore latches have been designed to be automatically released upon pulling outwardly upon a handle serving as a handle for the door, but the connection between the latch and handle was such that by pressing inwardly upon the handle, as in closing the door, a pressure would be applied to the latch directly opposed to its retracting movement, preventing free engagement of the latch with its keeper, so that it was necessary to close the door without pressing upon the handle to permit the handle to follow the keeper engaging movements of the latch, the handle first moving outwardly and then snapping inwardly during such movements of the latch. Obviously, any variation in the engaging relation of the latch with its keeper, as might be caused by warping of the door, sagging, or other such conditions, would be directly transmitted to the handle, so that it would either set away from the door surface, or would prevent full binding engagement of the latch.

According to the present invention a fixed normal relation of the handle is maintained with respect to the door surface, independ-

ently of the latch, and the latter is therefore permitted to function with full efficiency, irrespective of variation in the door structure.

A further object is to provide a latch including a detachable knob or handle, and which in the detached relation of such knob or handle will be substantially flush with the outer surface of the door, thereby greatly facilitating the packing and shipping of cabinets or the like equipped with the latches.

Another object consists in the pivotal mounting of a latch in a sheet metal bracket, which simultaneously serves as a pivot support and a stop for limiting pivotal movement of the latch in both directions, and further acts as a guard for the latch and its actuating spring.

Another object is to provide a latch member formed from a single piece of sheet metal folded upon itself, and with angular or offset ends forming the fulcrum, the offset portion serving both as a guard and retainer for the spring.

Still another object consists in providing, as one embodiment, a roller type of catch associated with the latch, and a lever handle connected to the latch in a manner to assist in the wedging engagement of the latch, this type being especially desirable for refrigerator use.

With the above and other objects in view, embodiments of the invention are shown in the accompanying drawings, and these embodiments will be hereinafter more fully described with reference thereto, and the invention will be finally pointed out in the claims.

In the drawings:

Fig. 1 is a horizontal sectional view of a door and casing, showing the latch, according to the present embodiment of the invention;

Fig. 2 is an inner end elevation of the latch, as shown in Fig. 1;

Fig. 3 is a perspective view showing the latch, keeper, and knob, in detached and separated relation;

Fig. 4 is a view, similar to Fig. 1, and showing the position of the latch and knob, as the former is released through opening the door;

Fig. 5 is a similar view, showing the position of the latch and knob, as the former is

retracted by the keeper through closing the door by pressure applied to the knob;

Fig. 6 is a detail sectional view of the knob attaching latch actuating rod and its guide support; and

Fig. 7 is a view, similar to Fig. 1, showing a modified form of the invention.

Similar reference characters indicate corresponding parts throughout the several 10 figures of the drawings.

Referring to the drawings, the latch is adapted to be secured at the inner side of a hingedly mounted door 10 having a flange 11 adapted to close against a casing or frame 12, the door being provided in inwardly spaced relation to its flanged edge with a drilled hole or passage 13 extending therethrough.

The latch, according to the present embodiment of the invention, comprises a bracket formed of sheet metal, and including a flat triangular base 14, provided centrally of its forward edge with an upwardly bent bearing support 15, serving as a latch 20 stop, and side ears 16 bent inwardly therefrom. Between the ears 16 there is secured a transverse pin 17 upon which the bell crank lever type of latch is pivotally mounted. This latch is preferably formed of a single 30 piece of sheet metal folded upon itself along the top edge 18, and comprises a nose portion 19, a rearwardly extending tail portion 20 having an upwardly projecting end 21, and downwardly extending mounting ears 35 22 bent outwardly and downwardly into spaced parallel relation with each other and pivotally engaged upon the pin 17 adjacent the inner surfaces of the ears 16. A coil spring 23 is coiled about the pin 17, one projecting end being engaged against the under surface of the upper lateral portion of the mounting ears 22, while the other end bears upon the base plate, whereby the latch 40 is pressed in counter-clockwise direction 45 against the portion 15 acting as a limiting stop. The forward edge of the nose portion 19 of the latch is cut away above the ears 22 to form a notch 24, and is rounded above said notch, as at 25, to provide a camming surface.

At the rearward portion of the base plate 14 there is provided an aperture 26 in which is secured the upper end of a tubular guide member 27, adapted to be engaged in the 55 drilled passage 13 in the door with its lower edge substantially flush with the outer surface of the door, the base plate being secured to the inner surface of the door by screws 28 engaged through holes 29 formed in the 60 forward corners of the plate.

Within the guide member there is slidably engaged a handle or knob attaching pull rod including an upper enlarged diameter portion 30, guided in the upper end, and a 65 smaller diameter stem portion 31, guided in

the inwardly flanged lower end 32, a coil spring 33 being coiled about the stem between said flanged end 32 and the shoulder of the upper portion 30 and normally pressing the pull rod inwardly, its inwardly moved or projected position being limited by a flange or flare 34 formed at the lower end of the pull rod adapted to seat within a recess 35 formed by counter-sinking the flange 32 of the guide member, so that with the handle or knob detached, as in Fig. 6, the end surface is flush with the outer door surface. The pull rod is provided with a threaded hole 36, within which the screw 37 of the knob 38 is adapted to be engaged. 70

At the inner end of the pull rod there is formed a stud 39, upon which is secured the base 40 of an angular yoke 41, having a slot 42 in its upright portion in which is engaged the tail portion of the latch. The slot 42 is of such length that a short lost motion space is provided above the tail piece 20 in the normal latched position of the latch, while a relatively long space is provided beneath said tail piece to permit independent retracting or keeper engaging movement of the latch with respect to the knob, as indicated in Fig. 5.

The keeper, adapted to cooperate with the latch, is formed of a strip of sheet metal, and consists of a base portion 43 adapted to be secured to the casing 12, as by screws 44, an angularly bent latch retaining or keeper portion 45, and an inclined strike portion 46, with which the rounded cam portion 25 100 is adapted to coact during closing of the door to force back the latch.

In operation, a pull upon the knob tilts the latch upon its pivot, releasing it from the keeper portion 45, and continued pull swings the door upon its hinges to open it. When the door is closed, either by pushing against its surface, or preferably by pushing directly upon the knob, the latch first engages the strike 46, camming back, as shown in Fig. 5, and thereupon engages the keeper portion 45, the latch spring automatically seating the latch with a binding closing pressure upon the door. During the closing operation the pressure upon the knob does not oppose the keeper engaging action of the latch, nor is this action imparted to the knob. The lost motion relation between the latch and the slotted yoke portion 41 permits full binding engagement of the latch under variations in the door or latch structure, as might be caused by warping of the door, or inaccurate attachment of the keeper plate. 110

In Fig. 7 there is illustrated a modified form of the invention, in which the mounting base for the latch consists of a base plate portion 47 and a three sided box structure 48 bent upwardly therefrom, in the side portions of which the latch is pivotally mounted on a pin 49. The latch is formed 125

of sheet metal folded upon itself along the edge 50, providing a smooth camming surface, and including a nose portion 51 and outwardly and downwardly bent spaced portions 52, pivotally engaged at their forward ends upon the pin 49 within the box structure 48, and provided at their rearwardly projected ends with a transverse pin 53 adapted for connection with the handle pull rod, presently to be described. A coil spring 54 about the pin 49 coacts in a similar manner to the first form to press the notch edge portion 55 of the latch into engagement with the keeper. The keeper, as shown in this embodiment, comprises a base plate 56 having an angular portion 57 in which a roller 58 is supported, the angle of the notch 55 being such that increasing inward movement of the latch increasingly presses the door closed with a wedging action.

The handle 59 is in the form of a lever, which is pivoted at 60 in a bracket 61 and is pivotally connected at 62 to the outer end of a pull rod 63, guided in a bushing 64 formed upon the base plate 65 of the bracket and engaged in a passage 66 in the door, the pull rod extending through said passage and being provided at its inner end with an enlargement engaged between the spaced ends of the latch and provided with a slot 67 engaged by the pin 53.

The operation in opening the door is substantially the same as in the first embodiment. In closing, however, an increased pressure may be applied upon the latch after it is engaged with the keeper by pressing the handle inwardly, this action pressing the door tightly closed with an increasing wedging action. This is especially desirable in refrigerator use, and in other uses where a very tight closure is desired.

It will be understood that the form of keeper and the type of handle shown in connection with either of the two embodiments illustrated may be used with the other.

I have illustrated and described a preferred and satisfactory embodiment of the invention, but it will be obvious that changes may be made therein, within the spirit and

scope thereof, as defined in the appended claims.

Having thus described my invention, what I claim and desire to secure by Letters Patent is:—

1. In a latch for a movable closure or the like, a bell crank latch member adapted to be projected and retracted and including rigidly connected nose and tail portions, a mounting bracket pivotally supporting said latch member, a spring acting between said bracket and latch member adapted to yieldingly press the latter to projected position, a normally projected actuating member adapted to have latch retracting movement in the opening direction of said movable closure and including a slotted portion engaged by the tail portion of said latch member, said latch member adapted to have retracting movement independently of the actuating member through free movement of said tail portion in said slotted portion, and spring means adapted to yieldably retain said actuating member in normal position independently of said latch member.

2. In a latch for a movable closure or the like, a bell crank latch member adapted to be projected and retracted and including rigidly connected nose and tail portions, a mounting bracket pivotally supporting said latch member, a spring acting between said bracket and latch member adapted to yieldingly press the latter to projected position, a normally projected actuating member adapted to have latch retracting movement in the opening direction of said movable closure and including a portion engaged by the tail portion of said latch member having a lost motion connection therewith adapted to permit retracting movement of said latch member independently of the actuating member, and spring means adapted to yieldably retain said actuating member in normal position independently of said latch member.

Signed at Lebanon, in the county of Boone and State of Indiana, this 15th day of January, 1926.

ANDREW J. STEWART.
